MULTIPLE BOILER FURNACE STEAM PLANT

Clyde W. Colby, Holyoke, Mass., assignor to General Electric Company, a corporation of New York

Application December 19, 1934, Serial No. 758,276

4 Claims. (Cl. 122—1)

The present invention relates to multiple boiler furnace steam plants particularly where a large number of relatively small capacity boiler furnaces are operated to supply a steam load of relatively large value.

5 One of the objects is to provide an improved construction whereby the boiler furnaces may be interconnected in groups in a confined space with practically all of the steam, water and flue pipes located below the furnaces.

10 Another object is to insure a proper supply of air for combustion in the furnaces while preventing heated air rising from the steam and flue pipes upwardly around the furnaces.

15 A further object is to provide an improved interconnecting arrangement for the groups of boiler furnaces so as to facilitate the steam, water and flue piping connections, maintain uniform combustion and steam generating conditions in each boiler furnace of a group, conserve the floor space required for installation of the groups of boiler furnaces and at the same time render each boiler furnace readily accessible for inspection and repair.

20 Other objects will appear from the following description of the accompanying drawings which illustrate a preferred embodiment of the invention in a relatively large capacity central steam plant employing a large number of automatic oil fired boiler furnaces of the type ordinarily used in domestic heating service.

25 In the drawings Fig. 1 is a schematic plan view of the multiple automatic oil fired boiler furnace steam plant; Fig. 2 is a sectional elevation of the steam plant shown in Fig. 1; Fig. 3 is a plan view of a single group of the boiler furnaces on an enlarged scale in order more clearly to show the improved interconnecting arrangement thereof and Fig. 4 is an elevation of the group of boiler furnaces shown in Fig. 3 with certain parts broken away and some parts omitted in order more clearly to reveal the details.

30 In the steam plant shown in Fig. 1 a plurality of groups of boiler furnaces G_1 to G_{12} are interconnected to supply steam to the steam main. To facilitate the steam, water and flue piping connections, the boiler furnaces in each group, are disposed in radially spaced relation and provided with converging steam connections, converging return water connections and converging flue connections which are shown more clearly in Figs. 3 and 4.

35 Each of the automatic oil fired boiler furnaces shown is of the type provided with a steam outlet connection 11 and a flue outlet 12 extending

from the rear of the furnace as disclosed in the copending application, Serial No. 676,651, filed June 20, 1933 by Henry S. Woodruff, and assigned to the assignee of my present invention although the present invention is not necessarily limited thereto. In each boiler furnace combustion is produced by suitable means such as an automatic oil burner mechanism located under the removable hood 13 . The combustion air is supplied to the burner mechanism from the surrounding atmosphere through the louvers formed in the air inlet conduit 14 .

40 As shown in Fig. 3 each group comprises five boiler furnaces F_1 to F_5 disposed radially about the vertical axis x with an angle of 72° between the center lines of the adjacent furnaces. In this way an efficient utilization of the floor space required for installation of the group of furnaces is obtained and at the same time each boiler furnace is readily accessible for inspection and repair.

45 In each group of boiler furnaces, a common steam collecting drum 20 is located on the vertical axis x considerably above the level of the steam outlets 11 of the boiler furnaces. The steam collecting drum 20 is connected to each of the steam outlets 11 of the boiler furnaces by the converging steam connection pipes 21 . Preferably these converging steam connection pipes 21 are of slightly spiralled form as indicated in Figs. 3 and 4 so as to obtain flexibility and thereby avoid excessive strains or stresses due to unequal expansion. The connecting pipes 21 preferably are welded at one end to the steam drum 20 and provided with a bolted flange fitting 22 at the other end for detachable connection with the boiler furnace steam outlet 11 .

50 Steam is supplied from the common steam drums 20 of each group of furnaces through a steam feeder 23 which extends downwardly through an opening 15 in the floor 16 upon which the boiler furnaces are mounted. A hand shutoff valve 24 preferably is provided adjacent drum 20 for cutting off each group of boiler furnaces from the steam lines.

55 In each group of boiler furnaces a common flue 25 is located on the vertical axis x below the bottom of the boiler furnaces and is provided with the converging flue connection pipes 26 for connection with the flue outlet 12 of each furnace. The converging flue connections 26 extend downwardly through the central circular opening 17 formed in the furnace supporting floor 16 concentric with the axis x about which the group of boiler furnaces F_1 to F_5 are mounted.

in radially spaced relation. A cutoff damper 27 is provided in flue 25.

A common return water drum 30 is disposed on the vertical axis x between the common steam drum 20 and the common flue 25 at the approximate level of the water line of the boiler furnaces indicated by the dotted line L. Water drum 30 is connected to each of the boiler furnaces in the group by means of the converging 10 return water connections 31 which are staggered or radially offset to obtain flexibility and facilitate installation. The common return water line 32 extends upwardly inside of the drum 30 to approximately the level of the water line L. A 15 pressure equalizing connection 33 extends between the top of the common return water drum 30 and the common steam drum 20. The hand shutoff valve 34 is provided for closing the equalizing connection 33. Similarly a hand shutoff 20 valve 35 is provided for cutting off the common water return drum 30 from the return water line 32. Also a blow-off line 36 with hand valve 37 is connected to the water drum 30.

It will be noted that with construction described the steam, return water and flue connections to each boiler furnace are readily removable. Thus in case failure of any boiler furnace occurs, the corresponding group of furnaces may be cut off from the steam, water, and 30 flue lines. The faulty furnace then may be quickly removed and a spare boiler furnace readily substituted.

Figs. 1 and 2 show the groups of boiler furnaces G₁ to G₁₂ located symmetrically on either side 35 of the steam main 10 which is removed entirely from the boiler furnace room and located below the floor 16 upon which the furnaces are mounted, thus being readily connected to an underground steam piping system. The steam main 40 10 is progressively reduced in diameter where the lateral steam feeders 40 connecting with the steam supply pipe 23 from the groups of boiler furnaces branch symmetrically therefrom as indicated by the dotted lines in Fig. 1. This insures a minimum pressure drop in the steam 45 lines with a minimum amount of piping when all or any part of the groups of boiler furnaces are operating to supply steam to the main 10.

A main return water distributing tank 45 is 50 located symmetrically between the groups of boiler furnaces directly above the steam main 10 on the furnace supporting floor 16. Branch feeder pipes 46 extend from each side of the water distributing tank 45 and are joined to the 55 return water line 32 of each group of boilers. Suitable condensate pumping means (not shown) are provided for automatically maintaining the water in tank 45 at the boiler water level L.

The main flue conduit 50 receives the products 60 of combustion from the various groups of furnaces through the lateral flue connections 51 which join with the common flues 25 of each group of furnaces. It will be understood that while not shown the main flue conduit 50 is 65 connected to a suitable stack, preferably with forced draft fans provided for insuring adequate draft conditions.

Any desired number of groups of boiler furnaces 70 may be operated to supply steam to the steam main 10 depending upon the load requirements. With the arrangement described, substantially uniform combustion and steam generating conditions are maintained in each boiler furnace irrespective of the number of groups operating.

Moreover a uniform water level is insured in each boiler furnace.

Due to the extension of the return water connection 32 into the common return water drum 30 to approximately the water level of the boilers 5 as shown in Fig. 4, in conjunction with the pressure equalizing connections 30, it is impossible to blow the water level down in any boiler furnace even though the manual steam shutoff valve 24 is inadvertently closed. By this arrangement 10 dangerous exposure of the crown sheets of the boiler furnaces is effectively prevented.

To insure an adequate supply of combustion air to the burner mechanism of the boiler furnaces as well as adequate ventilation of the power plant, a plurality of forced draft fans 60 are provided for forcing air under pressure into the room in which the groups of furnaces G₁ to G₁₂ are located. Preferably the forced draft fans 60 are located in alignment at one end of the boiler 20 room above the level of the furnaces so as to draw air from the outside and force the air to circulate in a sheet over the top of the furnaces. A portion of this air is drawn into each furnace through the louvers in the air inlet tubes 14 shown 25 in Fig. 4 during operation thereof. The remainder of the air passes downwardly over the furnaces and through the several central circular openings 17 in the floor 16 about which the furnaces are grouped. The air is then exhausted 30 from the space below the floor 16 by the exhaust blower 61. In order to insure uniform distribution of the air, the exhaust blower 61 is connected through the conduits 62 with a plurality of adjustable air inlet housings 63. These housings 35 are located in the space below floor 16 adjacent each group of the furnaces as indicated by the dotted lines in Fig. 1. By adjusting the relative size of the air inlet openings of the housings 63, uniform flow of air through the several central openings 17 may be obtained. With this improved downward air flow arrangement the boiler furnaces are effectively protected from any heat rising from the steam piping and from the flues.

By means of the present invention the entire 45 space required for installation of the large number of boiler furnaces is reduced to a minimum. Also the invention enables practically all steam and flue and return water connections to be removed from the boiler room proper into the 50 space below the floor supporting the boiler furnaces. Thus with the improved construction the installation of a multiple boiler steam plant may be made successfully in a confined space where otherwise this would not be possible.

What I claim as new and desire to secure by Letters Patent in the United States is:

1. In combination, a plurality of boiler furnaces disposed in radially spaced relation about a vertical axis and having converging steam connections extending from the upper part thereof and converging flue connections extending from the lower part thereof, a common steam collecting drum disposed on said axis and joined to said converging steam connections, and a common flue disposed on said axis and connected to said converging flue connections.

2. In combination, a plurality of boiler furnaces disposed in radially spaced relation about a vertical axis and having converging steam connections extending upwardly therefrom, converging water supply connections extending centrally therefrom and converging flue connections extending downwardly therefrom, a steam collecting drum, a water supply drum, and a flue all 70 75 80 85 90 95 100 105 110 115 disposed in spaced apart alignment on said axis and joined respectively to said steam connections, said water supply connections and said flue connections.

5. 3. In combination, a plurality of groups of boiler furnaces having a common water line, and each group having a common steam collecting drum and a common water supply drum separately connected to each furnace in the group 10 with the water drum extending above and below the water line thereof, a pressure equalizing connection between the steam and water drums in each furnace group, and a common water supply

tank having conduits opening into the common water drum of each furnace group at substantially the level of the common water line of the boiler furnaces.

4. A multiple boiler furnace plant having a supporting floor provided with an opening therethrough, a plurality of boiler furnaces mounted on said floor in radially spaced relation around said opening and having flue connections extending downwardly through said opening, and 10 ventilating means for forcing air from around said furnaces downwardly through said opening.
